UNITED STATES PATENT OFFICE.

CHARLES A. LUNDGREN, OF DAYTON, OHIO, ASSIGNOR, BY MESNE ASSIGNMENTS, TO THE NATIONAL CASH REGISTER COMPANY, OF DAYTON, OHIO, A CORPORATION OF OHIO, (INCORPORATED IN 1906.)

DRIVING MECHANISM FOR CASH-REGISTERS.

No. 895,873.

Specification of Letters Patent. Patented Aug. 11, 1908.

Application filed March 15, 1906. Serial No. 306,216.

To all whom it may concern:

Be it known that I, CHARLES A. LUNDGREN, a citizen of the United States, residing at Dayton, in the county of Montgomery and 5 State of Ohio, have invented certain new and useful Improvements in Driving Mechanism for Cash-Registers, of which I declare the following to be a full, clear, and exact description.

10 This invention relates to cash registers, and has for its object to provide an improved operating device for the same.

In establishments where the register is in almost constant or in frequent use, the continued operation becomes tiresome to the operator, and it is therefore desirable to provide a motor device which will save the operator this fatigue. Electric motors have been heretofore used in this connection, but 20 in many establishments the electric current necessitated for their operation is not to be had. In many such places, however, water power is available, and this invention is particularly designed to be used in establishments of that class.

25 The invention, therefore, comprises a water motor and connections for operating the register, and a key or equivalent for controlling the admission of fluid under pressure to 30 the motor.

With these and incidental objects in view, the invention consists in certain novel features of construction and combinations of parts, the essential elements of which are set 35 forth in appended claims and a preferred form of embodiment of which is hereinafter specifically described with reference to the drawings which accompany and form part of this specification.

40 Of said drawings: Figure 1 is a transverse elevation of a machine to which the motor may be adapted. Fig. 2 is a vertical section of the motor-cylinder and the controlling valve. Fig. 3 is an elevation showing the 45 motor attached to the register, and Figs. 4, 5 and 6 are details of construction.

Described in general terms, the machine comprises a series of keys 10 pivoted on a shaft 11 and arranged at the rear ends to operate the usual key coupler 12. The key coupler has fastened thereto a depending bar 13, having an anti-friction roller 14 at the end thereof adapted to move in a slot in the side of the machine. Mounted on a shaft 15

is a cam 16, arranged to rotate and move the 55 anti-friction roller 14 and thereby elevate the coupler 12. This shaft 15 has on the outside of the machine, as shown in Fig. 3, a pinion 17 geared to a segment 18. This segment has mounted thereon a spring 19 for returning it to its normal position, as shown in this figure, and is connected to a link 20 which is pivoted to the reciprocating piston 21 of the water motor. As shown in Fig. 2, this piston reciprocates in a cylinder 22, and 60 admission of fluid to the lower part of the cylinder is controlled by the valve mechanism 23, much as is usual in steam engines. Joined by a link 24 to the valve mechanism 23 is the key 25, which is pivoted on a shaft 70 26, and which controls the operation of the machine.

In Fig. 2 the valve mechanism is shown in its normal position, and when the key 25 is depressed this mechanism is raised, as will be 75 evident, to allow admission of the fluid to the cylinder through entrance port 27. The piston 21 thereupon rises, rotating-shaft 15 and cam 16, which thereby oscillates the key 80 coupler 12 to which the operated value key is coupled and operates the machine.

The apparatus as heretofore described is a thoroughly operative device, but additional mechanism has been provided to assist in the return of the controlling key 25 to its normal 85 position. A spring 28 is primarily provided for this purpose, and as is also shown there is a lever 29 pivoted on a shaft 30 and normally above and at one side of the key 25, as shown in Fig. 6. A detail view of the lever 90 29 is shown in Fig. 4, and it will be evident that the pin 30^a on this lever is adapted to ride on the cam 31, shown in detail in Fig. 5, and which is also on shaft 15. This shaft 15 when rotated in a clock-wise direction in 95 Fig. 3 will, as is evident, cause pin 30^a on lever 29 to be elevated. This lever 29 will also be moved laterally by leaf-spring 31^a, this motion being allowed by the cam-notch 32 on the lever 29, so that the lever 29 is not 100 only raised but is also allowed to swing laterally under pressure of the spring 31^a so that it is then directly over the key 25. A pin 32^a on the machine frame serves to swing the 105 lever 29 laterally as it moves upwardly, inasmuch as the pin is in the path of the cut away portion or cam notch 32 on the lever. When the pin 30^a rides off the high edge of

cam 31, lever 29 will drop to the position shown in Fig. 3, and will thereby give key 25 a tap to assist in its own return to normal position under control of its spring 28. A 5 spring 33 assists in the return of lever 29 to its normal position. The peculiar shape of the high part of cam 31, as shown in Fig. 5, is required by the fact that this cam oscillates and does not always move in the same 10 direction. When the pin 30^a drops from the high edge of the cam 31 it would be impossible to reversely rotate the cam, unless the cut-away portion, as shown in this figure, was provided.

15 While the form of mechanism here shown and described is admirably adapted to fulfil the objects primarily stated, it is to be understood that it is not intended to confine the invention to the one form of embodiment 20 herein disclosed, for it is susceptible of embodiment in various forms all coming within the scope of the claims which follow.

For convenience in illustration I have shown my invention as applied to a well 25 known type of machine in which a coupler is used to provide for the simultaneous operation of a number of keys. The invention however is not limited to use with this type 30 of machine nor to any type of machine in which the power is applied through key levers, but may equally well be used with many other types of machines such, for example as those in which the keys act as stops for movable parts, or in which the keys release parts from a holding device, or in fact 35 to any machine which is adapted to perform the functions of a cash register.

What is claimed is as follows;

1. In a cash register, the combination with 40 a main operating member, of a motor for moving same, a key controlling the motor, a lever for restoring the key to normal posi-

tion, a pinion driven by said motor, and a cam moved by said pinion and constructed to cause engagement of said key and lever. 45

2. In an accounting machine, the combination with a movable member, of an oscillating device for operating said member, and means for controlling said oscillating device comprising a link connected to said device, a cylinder, a piston in said cylinder connected to said link, a key, and a valve operated by said key and controlling the ingress and egress of fluid to said cylinder. 50

3. In an accounting device, the combination with an operating mechanism, of a motor for operating same, a movable key for controlling said motor, and means for returning the key to normal position comprising an oscillatory shaft, a cam on said shaft having a beveled face, a lever having a cam surface and a pin engaging said beveled cam, said lever engaging said key. 55

4. In an accounting device, the combination with a key of means for restoring said key to normal, comprising a lever pivoted to swing in two directions, springs for swinging said lever, a cam for moving the lever in one direction and a pin for moving the lever in another direction. 60

5. In an accounting device, the combination with a plurality of keys, a key coupler common thereto, a lever connected to said coupler, a cam for operating said lever, and a fluid operated motor for operating said cam, 70 said motor comprising a cylinder, a piston therein, and a valve controlling the ingress and egress of fluid to said cylinder. 75

In testimony whereof I affix my signature in the presence of two witnesses.

CHARLES A. LUNDGREN.
